UNITED STATES PATENT OFFICE.

DELOS ALFRED SMITH, OF LOCKE, MICHIGAN.

STOVE-PIPE THIMBLE.

SPECIFICATION forming part of Letters Patent No. 339,701, dated April 13, 1886.

Application filed August 20, 1885. Serial No. 174,870. (No model.)

To all whom it may concern:

Be it known that I, DELOS ALFRED SMITH, a citizen of the United States, residing at Locke, in the county of Ingham and State of Michigan, have invented certain new and useful Improvements in Stove-Pipe Thimbles; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention has relation to improvements in devices for holding the end of a stove-pipe inserted within the hole in a chimney; and it consists in the construction and novel arrangement of a chimney-thimble, whereby the pipe is securely held thereto and prevented from becoming displaced, and also serving to prevent smoke and fire from entering the room at this point of the stove-pipe, all as will be hereinafter fully explained, and particularly pointed out in the appended claim.

The annexed drawings, to which reference is made, fully illustrate my invention, in which Figure 1 represents a front view of my device, and Fig. 2 is a rear view of the same.

Referring by letter to the accompanying drawings, A designates the chimney-thimble, of the usual circular form, in which are constructed two slots, a a, and a perforation, b, and a flange, c, surrounding the opening d, through which projects the end of a stove-

pipe.

B indicates a circular clamping-plate consisting of two portions or halves, e e, which are pivoted to one another, as at f, and said

pivot-pin extends through the perforation b in the thimble and is headed, thus securing to the clamping-plate thereto, and preventing the two parts A and B from being separated. This clamping-plate is provided with inwardly-projecting pins g g, which pass through the slots a in the thimble, in which they play when the two halves of the clamping plate are manipulated in securing the pipe to the thimble.

The free ends of the clamping-plate are provided with projecting lugs h h, which are perforated to receive a bolt, i, having a securing-nut, k, by means of which the clamp is tightly drawn around the end of the stove-pipe.

It will be seen that after the stove-pipe is inserted through the thimble the two sections are brought together, the bolt screwed up, thus securely locking the pipe to the thimble. The slots in the latter serve to guide and hold the sections to the thimble.

What I claim, and desire to secure by Letters Patent, is—

The herein-described chimney-thimble, consisting of the thimble A, having the slots a, the plate B, composed of two sections pivoted to one another and to the thimble, as described, and provided with the pins g, extending through the slots a, and lugs h, having the securing bolt i, the whole adapted to operate as shown and described.

In testimony whereof I affix my signature in presence of two witnesses.

DELOS ALFRED SMITH.
